CLAIM

We claim the ornamental design for the multiple outlet surge strip, as shown and described.

DESCRIPTION

FIG. 1 is a top view of a multiple outlet surge strip design showing our new design;

FIG. 2 is a bottom view of the multiple outlet surge strip design of FIG. 1;

FIG. 3 is a left side view of the multiple outlet surge strip design of FIG. 1; where the right side view is identical to that of the left side view;

FIG. 4 is a front view of the multiple outlet surge strip design of FIG. 1; and,

FIG. 5 is a back view of the multiple outlet surge strip design of FIG. 1.
